UNITED STATES PATENT OFFICE.

FREDERICK M. HILL, OF CHICAGO, ILLINOIS.

SIGNALING DEVICE.

Application filed October 1, 1917. Serial No. 194,122.

To all whom it may concern:

Be it known that I, FREDERICK M. HILL, a citizen of the United States, and resident of Chicago, in the county of Cook and State 5 of Illinois, have invented certain new and useful Improvements in a Signaling Device, of which the following is a specification.

This invention relates to signaling devices, and is especially adapted for railway 10 crossings or other intersections of rights of way.

One of the objects of the invention is to give a signal in a positive manner when a car or train is approaching a place to be 15 guarded, and to positively retire the signal from view when there is no danger.

Another object is to insure the giving of the danger signal in case the signal mechanism or any part of the related system gets 20 out of order or becomes abnormal for any reason whatever.

Another object is to provide improved 25 signaling mechanism adapted to serve the purposes stated, and to meet the various requirements for successful operation.

These and other objects are accomplished 30 by providing, in a device of the class described, a signal member mounted for a turning movement, whereby it is retired from 35 and returned to signaling position, and an oscillating or waving movement by which to emphasize the warning of danger; the said turning movement serving to retire the signal when there is no danger by presenting 40 its edge to view, and to present the face of the signal to view to indicate danger; the last-named position being assumed whether or not the signal is waving, so that if the system is out of order as the result of an 45 interruption of power supply or becomes inoperative from any other cause, the rotary or turning movement will have taken place and put the signal in danger position. In the preferred embodiment, the turning and waving functions are adapted to take place without interfering one with the other, the mounting for securing the turning move-

ment being carried by the mounting which imparts the waving movement; said movements being developed by independent 50 means.

The invention is illustrated in the accompanying drawings, in which—

Figure 1 is a front elevation of the complete signal, parts being in section. 55

Figure 2 is a plan view of the signal operating mechanism.

Figure 3 is a sectional view taken in the plane of line 3—3 of Figure 1.

Figure 4 is a sectional view taken in the 60 planes of the irregular lines 4—4 of Figure 2.

Figure 5 is a diagram of the electrical connections; and

Figure 6 is a perspective view of one form 65 of armature.

The various novel features of my invention will be apparent from the following description and drawings, and will be particularly pointed out in the appended claims.

10 represents a signal member adapted to assume, by turning movement, either of two positions, namely a lower position shown in full lines in Figure 1 with its face presented to view, and an upper position shown by dotted lines in said figure with its edge 75 presented to view. This signal member is provided with a vertically extending stem 11 through which projects a pin 12 which extends outwardly through oppositely arranged slots 13 in a relatively stationary casing 14. 80 These slots 13 are curved or in the form of cams so that when the signal lever 10 is raised from its lower full line position, as shown in Figure 1, to its upper dotted line position, as shown in said figure, the signal member will be turned to an angle of 90°, 85 or any other predetermined angle, and will then be in non-signaling position with its edge presented to the highway. Similarly, when the signal member is lowered from its dotted line position to its full line position, 90 as shown in Figure 1, it will be turned back through the same predetermined angle into signaling position, and will present its face

to highway traffic and indicate danger. The lower and upper ends of the slot 13 have their walls arranged vertically for a short distance to form a lock with respect to the 5 pin 12 to prevent the signal member 10 from being turned by the action of the wind or other extraneous influence, and thus provide an effective means for locking the signal member in either of its two positions.

10 The casing 14 is supported by a pintle 14^a, and constitutes a swinging arm, the same being a pendulous arm in the preferred embodiment illustrated, and through this casing or arm oscillatory signalling movement is imparted to the signal member. To develop this oscillatory movement, the pintle 14^a is provided with a rock arm 15, one end of which is connected by a link 16 to the crank 18 of the gear wheel 17. Crank 18 is shorter than 15 the rock arm 15 so that rotary motion of the crank develops oscillatory motion in the rock arm, pintle, casing, and signal member, and causes the signal member to emphasize its warning by wig-wag motion in addition to presentation of its face to view. It will be seen that means for moving the signal member on its axis to change its presentation and the means for developing the wig-wag motion are independent and distinct in that 20 neither interferes with the other. In other words, the signal member can be dropped to danger position even though the means for developing the wig-wag movement became disarranged, and the fact that an operative 25 connection for rotating the signal on its axis extends through the casing through which the signal is wig-wagged does not interfere with the latter function.

30 The gear 17 is driven by a small pinion 19 on one end of a shaft 20 which carries upon its other end a larger gear wheel 21 which is in mesh with a second small pinion 22 on the shaft 23 of electric motor 24. This train of gearing permits a relatively small motor 35 to be used and to run at efficient speed without developing too rapid a wig-wagging motion, and also renders the motor sufficient to raise the signal member and overcome the 40 resistance of its rotating mechanism, and this multiplication of power and reduction of speed in the driving train, particularly when reinforced by the load imposed by the oscillating crank 18, rock arm 15, and wig-wag casing 14, effectually resists counter-revolution of the shaft when the motor is de-energized, as will be hereinafter explained.

45 Normally the motor is not in motion, and signal 10 remains stationary and in its elevated position when there is no danger to be announced. However, if danger develops, for instance, if a car approaches the crossing, the circuit of motor 24 is closed, as herein-after explained, whereby signal member 10 will receive a wig-wag motion through mechanism just described, after having been ro-

tated to visible position by means which will now be described.

50 Connected with the crank 18 is a shaft 25 upon which is loosely mounted a sheave 26, around which passes a flexible member 27, connected to stem 11 of the signal member 10, and thereby adapting the signal member to be raised or lowered by rotation of the shaft 25. Fixedly related to sheave 26, and therefore adapted to drive the same but free 75 from direct driving connection with shaft 25, is a drum 27 that has incorporated within it a winding 28 that develops electro-magnetism in the metal of the drum.

55 At the opposite end of the drum 27, and secured to the shaft 25 in a manner to be driven by said shaft, is a collar 38 carrying a radially extending arm or rod 37. Loosely mounted on the collar 38 between the arm 37 and the drum 27 is a disk 29 which serves as 80 the armature for the magnetic drum 27. This armature is provided with a projection 39 which lies in the path of movement of the arm 37 and is sufficiently long to be engaged by said arm when the armature 29 85 is drawn to the magnet. Rotation of shaft 25 by motor 24 during the attraction of armature 29 to drum 27 causes the said drum to rotate, and with it the sheave 26 to wind the 90 flexible connector 27' and raise and simultaneously rotate the signal member 10. De-energizing of the magnet of drum 27 permits the armature 29 to become free from the 95 drum 27 and sheave 26 so that the signal member 10 can gravitate and rotate to its lower signaling position. Drum 27 and armature 29 therefore constitute a clutch. For 100 reasons already explained, the resistance of the shaft 25 to counter-revolution is too great even when the motor 24 is deenergized, to 105 permit the signal member to gravitate to signaling position; hence, the signaling member remains elevated so long as the armature 29 is attracted to the magnetic drum 27. Surrounding the drum 27 are a series of electrical ring conductors that enter into controlling circuits. Of these, the central ring 34 is 110 interrupted by insulation at 34^a. Cooperating with this central ring are brushes or contact fingers 35, 36 (Figures 1 and 5) connected in motor circuit as shown in Figure 5. The relation of the brushes 35 and 36 and the ring 34 with its insulated portion 34^a is such that when the drum 27 has reached the position in which the signal member 10 is up, the 115 circuit to the motor is broken.

120 In the schematic view of Figure 5, which shows an arrangement of circuits which may be used in connection with the subject-matter of the present invention, A, B, 125 represent a section of railway track having its local source of current C. D, E, represent two conductors from a suitable source of electrical power. Connected across the rails of sections A, B, and in circuit with 130

the source C is a magnet 30 of relay 31, whose armature 32 and contact 33 are in circuit with line D, drum magnet 28 and line E. So long as there is no car upon the rails of section A, B, to short circuit magnet 30, the circuit remains closed at 5 32, 33; magnet 28 remains energized, armature 29 is attracted, and the signal member 10 is held elevated. But as soon as a car 10 enters the section A, B, the circuit of magnet 28 is opened by deenergizing of relay 31 and the signal automatically drops and assumes signaling position. Likewise in circuit with the conductors D and E is the 15 motor 24 through contacts 35, 36 and ring 34 on drum 27. So long as the drum is in position to hold the signal member 10 elevated, insulation 34^a (Figure 3) is under brush 36 and motor 24 is deenergized and 20 the signal remains inoperative. But as soon as relay 31 is short circuited by the presence of a car on section A, B, and drum 27 is permitted to rotate to drop the signal, the circuit of motor 24 is completed by 25 ring 34 and contacts 35 and 36, and the wig-wag motion proceeds continuously until the train leaves the section and relay 31 becomes reenergized and closes the circuit of magnet 28. As soon as this is accomplished 30 rotation, which is being imparted to shaft 35 of the motor 24, revolves the drum 27 to retire the signal member until the signal member reaches its limit of retirement from 35 signaling position, when the insulation 34^a will have arrived beneath the contact 36, and the motor will be arrested.

Any disarrangement of parts which leaves the drum 27 free to rotate will drop the signal member to danger position regardless of whether the circuits are such as to follow the drop with the wig-wag movement. The structure illustrated and described covers what is known in the signaling art as a three-position signal. The 40 three positions are as follows: (1) the normal position, in which the cable 27' holds the signal member 10 up out of conspicuous position, (2) in which the electromagnetic winding 28 allows the signal member 10 to drop to a conspicuous position and in which the motor 24 communicates a wig-wag motion to said signal member 10; and (3) the inoperative position in which the electrical 45 circuits are de-energized, as for example by an accident in which the signal member 10 is moved by gravity to a conspicuous position and will warn passers by but will have no wig-wag motion.

It is to be understood that there may be 50 various modifications of the invention herein particularly shown and described, and it is my intention to cover all such modifications which do not impart from the spirit and scope of the invention as set forth in 55 the following claims.

I claim:

1. In a waving signal, a signal device having an oscillating support on which it is mounted and through which it receives a continuing waving movement to express 70 a signal, said signal having a connection with said support through which it moves independently of its signaling movement, to and from signaling position on said support.

2. In a waving signal, a signal device having a swinging arm through which it receives an oscillatory signaling movement, and a rotary connection with said swinging arm through which it receives movement independently of the oscillatory movement to and from signaling position upon said arm.

3. In a waving signal, a signal device having a pendulous supporting arm through which it receives oscillatory signaling movement, and a connection through which it rotates about the longitudinal axis of the arm, to and from signaling position on said arm and independently of the signaling movement thereof.

4. In a waving signal, a signal device having a swinging arm through which it receives oscillatory signaling movement, with a longitudinal movement on said arm in the direction of the axis thereof, and a connection translating such longitudinal movement into rotation to and from signaling position thereon.

5. In a waving signal, a signal device, a pendulous arm having a pivotal bearing and supporting the signal device and imparting oscillatory signaling movement thereto, said signal device having sliding movement on said arm and a connection therewith developing rotation of the signal device from said sliding movement, and means imparting such sliding movement independently of the signaling movement.

6. In a waving signal, a signal device, a pendulous arm having a pivotal bearing 110 and supporting the signal device and imparting oscillatory signaling movement thereto, said signal device having sliding movement on said arm and a connection therewith developing rotation of the signal device from said sliding movement, and means imparting such sliding movement independently of the signaling movement; said last-named means comprising a flexible connector extending longitudinally of the arm, 115 past the pivot bearing thereof.

7. In a waving signal, a signal device, a pendulous arm having a pivotal bearing and supporting the signal device and imparting oscillatory signaling movement thereto, said signal device having sliding movement on said arm and a connection therewith developing rotation of the signal device from said sliding movement, and means imparting such sliding movement independently of 125 130

the signaling movement; said last-named means comprising a flexible connector extending longitudinally of the arm, past the pivot bearing thereof, and a winding sheave 5 for said connector.

8. In a waving signal, a signal device having a swinging arm through which it receives oscillatory signaling movement, with a longitudinal movement on said arm in the 10 direction of the axis thereof, and a connection translating such longitudinal movement into rotation to and from signaling position thereon; said last-named connection comprising telescoping members carried, respectively, by the signal device and arm, and a cam-slot and pin carried by the respective telescoping members.

9. In a waving signal, a signal device having a swinging arm through which it receives an oscillatory signaling movement, a rotary connection with said swinging arm through which it receives movement independently of the oscillatory movement to and from signaling position upon said arm, 20 and means for imparting the respective movements, comprising a crank shaft linked to said arm, a winding element mounted on said crank shaft, and a flexible connector between said winding element and the signal device.

10. In a waving signal, a signal device having a swinging arm through which it receives an oscillatory signaling movement, a rotary connection with said swinging arm through which it receives movement independently of the oscillatory movement to and from signaling position upon said arm, and means for imparting the respective movements, comprising a crank shaft linked 30 to said arm, a winding element mounted on said crank shaft, a flexible connector between said winding element and the signal device, an electric motor for said crank shaft, and an electric clutch establishing driving connection between said crank shaft and winding element.

11. In a waving signal, a signal device having a swinging arm through which it receives an oscillatory signaling movement, a rotary connection with said swinging arm through which it receives movement independently of the oscillatory movement to and from signaling position upon said arm, and means for imparting the respective movements, comprising a crank shaft linked 40 to said arm, a winding element mounted on said crank shaft, a flexible connector between said winding element and the signal device, an electric motor for said crank shaft, and an electric clutch establishing driving connection between said crank shaft and winding element; said motor driving the crank shaft through power increasing and speed reducing gear, whereby unwinding load exerted by the signal device through the wind-

ing element upon the crank shaft is reduced in transmission back to the motor and resisted thereby.

12. In a waving signal, a signal device having a swinging arm through which it receives an oscillatory signaling movement, a rotary connection with said swinging arm through which it receives movement independently of the oscillatory movement to and from signaling position upon said arm, and means for imparting the respective movements, comprising a crank shaft linked to said arm, a winding element mounted on said crank shaft, a flexible connector between said winding element and the signal device, an electric motor for said crank shaft, and an electric clutch establishing driving connection between said crank shaft and winding element; the circuit of the motor being controlled by the winding element, and the circuit of the electric clutch for the winding element being controlled by the condition to be signaled.

13. A railway signal of the class described, including, in combination, a signal element, supporting means therefor, connections between said supporting means and said element by means of which the action of gravity tends to cause said element to assume a position to indicate danger, electrical controlling means for said signal element, said controlling means including means for permitting said signal element to assume a position to indicate danger in the event of failure of said controlling means, and means for transmitting wig-wag motion to said signal element when said signal element is in danger position.

14. A railway signal of the class described, including, in combination, a signal element, supporting means therefor, connections between said supporting means and said signal element by means of which the action of gravity will cause said element to rotate to cause said signal element to indicate danger, motive means for operating said signal in opposition to gravity, and electrical controlling means for said signal element, said electrical controlling means including means for permitting said signal to move to a position to indicate danger in the event of failure of said electrical controlling means, and means for transmitting wig-wag motion to said signal element when said signal element is in danger position.

15. In a railway device of the class described, the combination of a rotatable signal, supporting means therefor, the face of which signal is turned from view to indicate safety and which is presented to view to indicate danger, connections between said supporting means and said signal by means of which the action of gravity will cause said signal to rotate to cause said signal to indicate danger, motive means for rotating

said signal in opposition to the force of gravity to a position to indicate safety, and electrical controlling means for said signal, said electrical controlling means including 5 means for permitting said signal element to move to a position to indicate danger in the event of failure of said electrical controlling means, and means for transmitting wig-wag motion to said signal element when 10 said signal element is in danger position.

16. In signal apparatus, in combination, a gravity responsive signal member, power means, and connecting means including speed reduction gearing between said power 15 means and said signal member whereby said power means may raise said signal member against the force of gravity and rotate same about its axis, said connecting means including mechanism by means of which 20 said power means may communicate wig-wag movement to said signal member, said connecting means including electromagnetic clutch means through which said power means may raise said signal member, said 25 gearing being non-reversible whereby said signal member is held in raised position while said clutch means is energized.

17. A railway signal of the class described including, in combination, a signal 30 element, supporting means therefor, connections between said supporting means and said element by means of which the action of gravity tends to cause said element to rotate to assume a position to indicate danger, electrical controlling means for said 35 signal element, said controlling means including means for permitting said signal element to assume a position to indicate danger in the event of failure of said controlling means, and means for transmitting wig-wag motion to said signal element when 40 said signal element is in danger position.

18. A railway signal of the class described, including, in combination, a signal element, 45 supporting means therefor, connections between said supporting means and said element by means of which the action of gravity tends to cause said element to rotate to assume a position to indicate danger, power means, and operating means between 50 said power means and said signal member whereby said power means, operating through said operating means, may raise said signal member against the force of gravity, mechanism by means of which said 55 power means may communicate attention attracting movement to said signal element, said operating means including electromagnetic clutch means and gearing whereby the 60 power means may raise said signal member, said gearing being non-reversible whereby said signal member is held in raised position while the clutch means is energized.

19. A railway signal of the class de- 65 scribed, including, in combination, a signal

element, a motor, connections between said motor and said element including a clutch member and gearing, and means cooperating with said gearing and said signal element for giving said signal element a wig-wag motion about a predetermined axis, said connections including means for turning said signal about a line perpendicular to said axis said clutch member controlling the operativeness of said connections. 70

20. A railway signal of the class described, including, in combination, a signal element, a support for said element, and means cooperating with said support for communicating motion to said element axially of said support and rotatable relative thereto, controlling means for said motion communicating means, said controlling means including means for permitting said signal element to move to a position to indicate danger in the event of failure of said controlling means, and means for communicating wig-wag motion to said support. 80

21. In signal apparatus, in combination, a signal member, a longitudinal support therefor, power means for raising said signal member against the force of gravity axially of said support and, in co-operation with said support, communicating a turning movement to said member about the axis of said support, said power means including a motor and connecting means between said motor and said signal member, connections by which said power means may communicate attention attracting movement to said signal member, said connecting means including electromagnetic clutch means and gearing whereby said power means may raise said signal member, said gearing being non-reversible whereby said signal member is held in raised position while said clutch means is energized. 90

22. In signal apparatus, in combination, a signal member, a longitudinal support therefor, power means for raising said signal member against the force of gravity axially of said support and, in co-operation with said support, communicating a turning movement to said member about the axis of said support, said power means including a motor and connecting means between said motor and said signal member, connections by which said power means may communicate attention attracting movement to said signal member, said connecting means including clutch means and gearing whereby said power means may raise said signal member by means of said connections, said gearing being non-reversible whereby said signal member is held in raised position while said clutch means is operative, said apparatus including electro-magnetic means for holding said clutch means in clutching position, 105

23. In signal apparatus, a signal member, power means, said power means including a 110

motor and connecting means between said motor and said signal member for communicating a wig-wag motion to said signal member or for raising said signal member against the force of gravity, said power means also including a clutch between said motor and said signal member, and electromagnetic means for holding said clutch in clutching position to hold said signal member in raised position when said motor is de-

energized and to permit said signal member to drop by gravity when said electromagnetic means is de-energized, and controlling means for said signal member to cause said signal member to have a turning movement ¹⁵ about a vertical axis to a conspicuous position when said signal member drops.

Signed at city of Chicago, State of Illinois, this 27th day of September, A. D. 1917.

FREDERICK M. HILL.
